PETER J. DE DOES, OF TOLEDO, OHIO, ASSIGNOR TO THE TOLEDO PARLOR FURNITURE COMPANY, OF TOLEDO, OHIO, A CORPORATION OF OHIO.

SOFA-BED.

1,288,529.

Specification of Letters Patent. Patented Dec. 24, 1918.

Application filed January 24, 1916. Serial No. 73,893.

To all whom it may concern:

Be it known that I, PETER J. DE DOES, a citizen of Holland, and a resident of Toledo, in the county of Lucas and State of Ohio, have invented a certain new and useful Sofa-Bed; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to sofa-beds, and particularly to those of the foldable multiple section bed-frame and outwardly overturning seat type.

An object of my invention is the provision, in a bed of the class described, of simple and efficient means which is operable by folding and unfolding movements of the seat to respectively automatically lock together and release two relatively folded sections of the bed-frame at predetermined points in the folding and unfolding movements of the bed-frame.

A further object of my invention is the provision of a simple, improved and highly efficient bed of the character described, whereby to enhance the practicability and commercial value thereof, as will be apparent to persons skilled in the art from the following detailed description of the invention.

While the invention, in its broader aspect, is capable of embodiment in numerous forms, a preferred embodiment thereof is illustrated in the accompanying drawings, in which,—

Figure 1 is an end elevation of a sofa-bed embodying the invention, with the bed-frame and seat in closed or folded position and with an end portion of the sofa frame broken away. Fig. 2 is a similar view thereof with the bed-frame in full open or unfolded position. Fig. 3 is a plan view of a side portion of the bed-frame and seat in unfolded position. Figs. 4 and 5 are enlarged side elevations similar to Fig. 2, with the bed-frame in different stages of a folding or unfolding movement thereof. Fig. 6 is an end view of the bed-frame carrying box or frame with the seat-frame in normal closed position thereover. Fig. 7 is a bottom inner perspective view of an end por-

tion of Fig. 5 with parts broken away. Fig. 8 is a perspective view of the seat-frame and portions of the bed-frame in unfolded position with a modified form of leg controlling means associated therewith. Fig. 9 ⁶⁰ is an enlarged perspective view of an outer end portion of the bed-frame in usable position, and Fig. 10 is an enlarged perspective view of portions of the seat-frame, bed-frame and controlling means for the seat-frame leg with the parts in open position.

Referring to the drawings, 1 designates a sofa frame and 2 the outwardly overturning seat-frame thereof, which is carried by one of the foldably connected bed-frame ⁷⁰ sections, as hereinafter fully described.

The foldable bed-frame comprises, in the present instance, the inner, intermediate and outer major sections 3, 4 and 5, respectively, and the minor or spacing sections 6 and 7, ⁷⁵ the section 6 serving as a spacing means for and having its side bars pivotally connecting the adjacent ends of the respective side bars of the major sections 3 and 4, and the minor section 7 serving as a spacing means ⁸⁰ for and having its side bars pivotally connecting the adjacent ends of the respective side bars of the major sections 4 and 5, as shown and as well understood in the art.

The bed frame, in the present instance, is ⁸⁵ carried by and adapted to fold within a frame or box 8 that is preferably removably mounted in the sofa frame in any suitable or convenient manner and below the normal or inwardly folded position of the ⁹⁰ seat frame 2.

The frame is open at its top, and also at its bottom, if desired, and has its front side 8^a of shallow form, as shown.

The inner section 3 of the bed-frame is ⁹⁵ supported within the frame 8 by a folding link construction, which will now be described. A link 9 pivotally rises from each end of the frame 8 at the inner side thereof, being pivoted thereto as at 10, and is ¹⁰⁰ pivoted at its upper end to a horizontally-disposed bar 11, which extends transversely of the frame 8 at the respective end thereof and is pivoted at its rear end to a link 12, in the present instance in slightly spaced relation to its pivotal connection with the link 9. The upper end of the link 12 is pivoted, as at 13, to the respective side of the bed-frame section 3 adjacent to its rear end. It is thus apparent that the links 9 ¹⁰⁵ 110

and 12 form a toggle connection between the frame 8 and the bed-frame section 3, the bar 11 serving as a control means for the bed frame raising and lowering movements 5 of said links.

- The forward end of each bar 11 is pivoted, as at 14, to a respective link 15, in the present instance substantially midway between the ends of such link, and the link is pivoted 10 at its lower end to the forward end portion of the respective end of the frame 8, as at 16, and has its upper end terminating substantially in a plane with the bed-frame section 3, when in raised or usable position, 15 and pivotally connected, by a forwardly extending bar 17, to the respective side of the intermediate major bed-frame section 4 slightly in advance of its pivotal connection with the minor section 6, as at 18. It is 20 thus evident, especially by reference to Fig. 5, that upon a raising and rearwardly folding movement of the bed-frame section 4 with respect to the section 3, the bar 17 will communicate a rearward collapsing 25 movement to the link 15, and said latter link will in turn communicate collapsing movements to the links 9, 12 through the medium of the bar 11. The forward or inner end of each bar 11 is in supporting connection 30 with the respective side of the bed-frame section 3 adjacent to its forward or inner end through a link 19, which is pivoted to the bar 11, as at 20, and to the bed-frame section 3, as at 21.
- 35 A control-bar 22 is provided at each side of the bed-frame and is pivoted at its rear end to a standard 23, which fixedly rises from the adjacent end of the frame 8 near its rear portion, said control bar having its 40 forward end pivoted to the forward end portion of the respective side of the bed-frame section 3, as at 21, or in common with the pivotal connection of the link 19 therewith. The control bar 22, in the present 45 instance, is of L-form and co-operates with the bed-frame supporting link means above described to control the raising and lowering movements of the inner bed-frame section 3. The link means which I have illustrated and described for supporting and controlling the raising and lowering movements of the bed-frame section 3, when the bed-frame section 4 is unfolded or folded 50 with respect to the section 3, is substantially 55 the same as that described in my former application, Serial No. 39,316, filed July 12, 1915, and is therefore not claimed herein.

The sofa frame 1 is provided at its front side with a front board or panel 24, which 60 extends upward from the lower edge of the frame 8 to the lower front edge of the seat-frame 2, when in closed or usable position, as shown in Fig. 1, and has its lower edge pivoted, as at 25, to the lower edge of 65 the front side portion 8^a of the frame 8 for

outward swinging movements with respect thereto. A link 26 connects each end portion of the front board or panel 24 to the upper end portion of the link 15, as at 27, so that the movements of the board 24 with respect to the sofa frame are controlled by movements of the links 15. The connection between the links 15 and board 24 is such that a raising of the links 15 to upright position causes an outward swinging 75 of the board 24 to reclining position, and a rearward swinging of the links 15 to reclining position causes an upward swinging of the board 24 to upright front closing position with respect to the frames 1 and 8. 80

The outer end of the bed-frame, when in unfolded position, is supported at each side thereof by a leg 28, which is pivoted to the outer section 5 of the bed-frame adjacent to its outer end for rearward folding 85 movements thereagainst. A link 29 pivotally connects each leg 28 with the forward end portion of a bar 30, which is disposed along the inner side of the respective side bar of the section 5 and is pivotally connected to the forward end of the spacing link 7 in offset relation to the pivotal connection between the links 5 and 7, as shown at 31, whereby a folding of the section 5 with respect to the section 7 causes a folding 95 of the leg 28 against the section 5, as is well understood in the art.

A foot-piece 32 is pivotally carried by the outer end of the outer major section 5 of the bed-frame to have folding or unfolding 100 movements with respect thereto and, in the present instance, has its ends pivoted to the respective side bars of the section 5, as at 33. A catch-arm 34 is pivoted to each side bar of the bed-frame section 5, as at 105 35 and has its free end angled and provided with a longitudinally extending slot 36 for receiving a pin 37 on the respective end of the foot-piece 32. The outer end of the catch-arm 34 is provided with a seat 38 for resting on a stud 39 on the frame section 4 when the section 5 is turned thereover, the inner end of said seat being preferably shouldered, as shown in the drawings. A finger 40, in the present instance, projects 110 transversely from the free end of the catch-arm 34 away from the shouldered end of the seat 38 and in the general direction of extension of the major portion of the arm 34 from the angled slotted end portion 115 thereof. When the foot-piece 32 is placed in folded relation to the section 5, as shown in Fig. 4, the catch-arm 34 is moved into position for its seat 38 to register with and rest on the stop-pin or stud 39 on the section 4 120 when the sections 4 and 5 are in folded relation, and the catch-finger 40 is disposed in substantial parallelism with the section 4 and adjacent to the upper edge thereof. 125 A bar 41 is carried by each side bar of the 130

bed-frame section 4, preferably at the inner side thereof, for reciprocatory movements lengthwise of the bed-frame, and is provided with a transversely projecting catch-pin 42, which upon outward movements of the bar with respect to the bed-frame is caused to move over the catch-finger 40 and in catch engagement therewith to coöperate with the arm 34 to retain the sections 4 and 5 in folded relation and to hold the outer end of said arm in stop engagement with the pin 39. The bars 41 are slidingly carried by the respective side bars of the bed-frame section 4 by pin-and-slot connection therewith, as at 41^a, Fig. 8. The means employed for controlling the reciprocatory movements of the catch-bar 41 will be hereinafter described.

The seat frame 2 has each end thereof connected to the major section 4 of the bed-frame at the bottom side thereof when unfolded, by a pair of crossed links 43 and 44, which are pivoted together at their centers, as at 45, the link 43 being pivoted to the seat-frame adjacent to the edge thereof which is disposed forward when in unfolded position, as at 46, and having its other end pivoted to the respective side of the bed-frame section 4, as at 18, in the present instance, or in common with the pivotal connection of the bar 17 with said bed-frame section. The other link 44 of each side has one end provided with a pin 47, which projects into a slotted bar 48 of the seat-frame for limited movements transversely of the seat-frame and has its opposite end provided with a pin 49, which projects into the longitudinally-disposed slot 50 in the respective side bar of the bed-frame section 4, said slot-and-pin connection 49 and 50 between the bar 49 and bed-frame section 4 being disposed adjacent to the forward end of said section, as best shown in Fig. 4.

The pin 49 has connection with the forward end of the catch-bar 41 at the opposite side of the respective side bar of the bed-frame section 4 to the link 44, and is the means for controlling the longitudinal movements of said catch-bar relative to the bed-frame section. When the bed-frame and seat-frame are in unfolded position, as shown in Figs. 2 and 4, the weight of the seat-frame causes it to lower with respect to the bed-frame until the pins 47 and 49, carried by the respective ends of the link 44, move into contact with the inner or adjacent ends of the slots in the seat-frame and bed-frame section into which they respectively project, and when the link 44 is in this position with respect to the bed-frame section 4, the catch-bar 41 is retained at the limit of its rearward movement with respect to said section and with its catch-pin 42 in released position with respect to the catch-finger 40.

It is thus evident that the gravity or lower-

ing movement of the seat-frame 2 with respect to the bed-frame section 4, when said parts are swung outward from folded position, will cause an automatic release of the catch-pin 42 from holding engagement with the catch-finger 40, and that a raising of the outer edge of the seat-frame 2 with respect to the bed-frame section 4, when in unfolded position, will move the pin 49 on the link 44 to the outer end of its slot and effect an outward drawing of the catch-bar 41 with respect to the bed-frame section 4 and a consequent movement of the catch-pin 42 into catch engagement with the catch-finger 40, as illustrated in Fig. 5.

The front edge of the seat-frame 2 is connected at each end thereof to the respective spacing section 6 of the bed-frame by a link 51, which is pivoted at one end to a bracket 52 projecting downward or outward from the lower or outer edge of the bed-frame section 6 intermediate its ends, and is pivoted at its opposite end to a bracket 53 on the inner side of the front piece of the seat-frame. The link connection 51 between the front edge of the seat-frame and the bed-frame section 6 permits the seat-frame to swing outward with respect to the bed-frame section 4, being guided in such swinging movement by the links 43, and to be disposed in adjacent collapsed position with respect to the bed-frame section 4, with the link 51 in parallel relation to the sections 6 to which they are attached and at right angles to the section 4 when the seat-frame and bed-frame section 4 have been raised to or are in right-angle position with respect to the spacing section 6, as shown in Fig. 5.

In Figs. 1, 2, 3, 4, 5 and 10, the seat-frame 2 is shown as provided at the edge thereof, which is disposed forwardly when the seat-frame is in unfolded position, with a supporting leg 54 that is pivoted, as at 55, to said edge of the seat-frame for folding or swinging movements lengthwise of the seat-frame and transversely of the bed-frame. One of these legs is provided adjacent to each end of the seat-frame and each is connected with the respective link 44 by an intermediate mechanism, which communicates folding and unfolding movements to the leg from predetermined movements of said link. The mechanism employed for such purpose, in the present instance, comprises a bar 56 which is pivotally connected at one end to the pin 47 of the link 44, and projects therefrom to adjacent the rear edge of the seat-frame where it is connected to one arm of a bell-crank lever 57 and is fulcrumed for horizontal rocking movements to the seat-frame. A link 58 extends lengthwise of the rear edge portion of the seat-frame 2 and connects the other arm of said lever 57 to a slide-bar 59, which is provided for reciprocatory movements lengthwise of

80

120

125

130

the seat-frame and has one end extending without the rear edge of said frame and connected by a link 60 to the upper end of the leg 54 in offset relation to its pivot 55, whereby reciprocatory movements of the link 60 will impart folding and unfolding movements to the leg 54 with respect to the seat-frame.

In Fig. 8, the legs 54 of the seat-frame 10 are shown as disposed at the ends thereof for swinging movements transversely of the seat-frame or lengthwise of the bed-frame, each leg being pivoted to the seat-frame, as at 61. A pin 62 projects from each leg 54 15 at a point below its pivot, when the leg is in upright position, and this pin projects through a segmental slot 63 in the seat-frame end and connects directly to a bar 64, which lies along the inner side of the seat-frame 20 end and connects the pin 62 to the pin 47 on the link 44. It is thus evident that a movement of the pin 47 toward the forward edge of the seat-frame 2 will communicate a folding movement to the connected 25 link 44 with respect to the seat-frame, and vice versa.

Each end of the seat-frame 2 carries a pivoted finger 65 at its outer side, which finger is pivoted to the seat-frame, as at 66, 30 and is normally held in engagement with a stop-pin 67 by a coiled contractile spring 68. When the finger 65 is in normal position it projects from the inner side of the seat-frame 2 at a right angle thereto, or 35 substantially so, in position for its free end, which is notched, to bear against a registering pin 69 on the adjacent end of the frame 8, when the seat-frame is swung downwardly over the frame 8, as best shown in Fig. 6.

40 The finger 65 engages with the pin 69 when the rear edge of the seat is a short distance above its normal position on the frame 8, and swingingly supports the rear end of the seat-frame when the said frame is being 45 moved rearward over the frame 8 into proper resting position thereon, the finger 65 swinging away from the stop-pin 67 as the seat-frame is moved rearward to its normal resting position. The provision of the 50 finger 65 and coacting pins 69 not only facilitates the placing of the seat-frame in its normal resting position over the frame 8, but also serve to lock the seat-frame against a forward sliding movement on the 55 frame 8, it being necessary to swing the rear edge of the seat-frame upward and forward in order to move it relative to the frame 8. It is also found in practice that the weight of the rear end portion of the 60 seat-frame and the bed-frame parts carried thereby on the fingers 65, after their upper ends have been moved rearward out of direct vertical alignment with the pins 69, will cause an automatic shifting or movement 65 of the seat-frame and parts carried thereby

to normal resting position on the frame 8, thus obviating the necessity of giving the seat frame a rearward push when lowered on the frame 8 in order to place it in proper position thereon.

In order to counterbalance the weight of the seat-frame 2, and the bed-frame parts which are carried thereby, and to render it easy for an operator to move the bed and seat frames from folded to unfolded position, and vice versa, I connect each link 15 of the bed-frame supporting means to a slide-plate or member 70 by a link 71, said slide-plate being guided for reciprocatory movements transversely of the frame 8 by 75 a slotted guide-plate or member 72, which is secured to the adjacent end portion of the frame 8 at the lower edge thereof. I also connect a coiled contractile spring 73 at one end to the slide-plate 70 and at its other 80 end to the forward edge portion of the frame 8, as at 74. When the link 15 is in inclined position, which position it assumes when the bed-frame or the sections 3, 4 and 6 thereof are in unfolded position, the tension of the spring 73 is reduced, due to the slide-plate 70 standing at the forward end of its movement, or in adjacent relation to the far end of the spring. Upon a folding 85 of the bed-frame sections 4 and 6 and seat-frame 2 with respect to the bed-frame section 3, the link 15 lowers to reclining position and causes the slide-plate 70 to move rearward and effect a further stretching of the spring 73 so as to increase its tension and to cause it to have the greatest tension 90 when the bed and seat-frames are in completely folded position, as is apparent by reference to Figs. 1, 4 and 5.

The operation of my improved sofa-bed 105 is as follows: To unfold the seat and bed-frames, the operator pulls upward and forward on the rear edge of the seat-frame, and, due to the assistance, or the counter-balancing action, of the springs 73 on the bed-frame raising means, is enabled to easily swing the seat-frame 2 and bed-frame sections 4, 5, 6 and 7 forward to the unfolded 110 position shown in Fig. 4, the supporting mechanism for the rear end of the bed-frame at the same time being automatically operated to raise such end of the bed-frame to operative position. As the seat-frame and bed-frame sections 4, 5, 6 and 7 lower 115 to the reclining position shown in Fig. 4, the weight of the bed-frame causes it to swing downward in vertically spaced relation to the bed-frame section 4 until the links 43 and 44 have reached the limit of their opening movement, which movement is determined by the length of the slots in which the pins 47 and 49 of the link 44 work. This lowering movement of the seat-frame with respect to the bed-frame section 4 is controlled both by the links 43 and 44 120

and the links 51. The movement of the seat-frame 2 to its lowered position with respect to the bed-frame section 4 causes a rearward movement of the catch-bar 41 to place its catch-pin 42 in released position with respect to the catch-finger 40, thus permitting an unfolding of the frame section 5 with respect to the section 4. The lowering of the seat-frame 2 with respect to the bed-frame section 4 also causes a movement of the mechanism connecting the links 44 with the legs 54 to swing the same into inclined or seat-supporting position, as illustrated in Figs. 2, 4, 8 and 10. When the bed-frame section 5 is unfolded with respect to the section 4, the legs 28 at the outer end of the bed-frame are automatically moved to unfolded or bed-frame supporting position, and a movement of the foot-piece 32 to open position draws the catch-arms 34 to the upright or inoperative position shown in Figs. 2 and 9. The unfolding of the bed-frame with respect to the sofa frame causes an outward swinging of the front board or panel 24 of the sofa frame, due to the connection between said board and the link mechanism supporting the inner bed-frame section.

It will be understood from the above description that in folding the bed-frame the operator first folds the foot-piece 32 in reclining position over the bed-frame section 5, thereby moving the catch-arms 34 into operative position. He then folds the bed-frame section 5 over the section 4, the folding movement being stopped when the sections 4 and 5 are in substantially parallel relation by reason of the seats 38 at the outer ends of the catch-arms 34 striking and resting on the stop-pins 39 at the respective sides of the bed-frame section 4, as shown in Fig. 4. The operator next raises up on the forward edge portion of the seat-frame 2 to effect a drawing of the seat-frame 2 toward the bed-frame section 4 and also to raise the bed-frame sections 4, 5 and 7 to effect a folding thereof over the inner bed-frame section 3. The relative upward or inward movement of the seat 2 with respect to the bed-frame section 4, which is permitted by reason of the loose connection of the ends of the links 44 with the respective seat-frame and bed-frame section 4, causes a folding of the legs 54 with respect to the seat-frame and also a forward or outward movement of the catch-bar 41 with respect to the bed-frame section 4 and consequent movement of the catch-pin 42 over and in catch engagement with the catch-finger 40 of the arm 34, thus locking the bed-frame sections 4, 5 and 7 in folded relation, as shown in Fig. 5. The raising and rearward folding of the bed-frame section 4 over the bed-frame section 3 causes a collapsing of the link mechanism supporting the section 3, and also effects a drawing of the board or panel member 24 in closed relation with respect to the front of the sofa frame. As the seat-frame 2 lowers over the part or frame 8 of the sofa frame, the fingers 65 on the ends of the seat-frame move into resting engagement on the pins 39 carried by the ends of the frame 8, and cause the seat-frame to swing rearward into normal closed position instead of permitting it to remain in partly forwardly projecting relation to the frame 8.

It is evident that I have provided simple and efficient complementary means which are carried respectively by different sections of the bed-frame, one being automatically operable by folding and unfolding movements of the seat-frame with respect to the bed-frame to coöperate with the other to unlock or lock the respective sections in folded relation when the seat-frame 2 is raised or lowered with respect to the bed-frame section by which it is carried. It is also evident that the movements of the seat-frame with respect to the bed-frame section 4 not only control the locking and releasing movements of the catch means for the folded bed-frame section, but also control the movements of the seat-frame supporting legs.

I wish it understood that my invention is not limited to any specific arrangement, construction or form of the parts, as it is capable of numerous modifications without departing from the spirit of the claims.

Having thus described my invention, what I claim as new, and desire to secure by Letters Patent, is—

1. In a device of the class described, a plurality of foldably connected bed-frame sections, a seat-frame carried by one of said sections for folding and unfolding movements therewith and for movements relative thereto, and mechanism having parts carried by different of said sections and operable, by predetermined relative movements of said seat-frame and its carrying section, to lock together or release the sections carrying said parts.
2. A plurality of foldably connected bed-frame sections, in combination with a seat-frame mounted for movements relative to the bed-frame, complementary section fastening means carried by different sections, and means automatically operable, by movements of said seat-frame, to move one of said fastening means into and out of engaging relation to its companion.
3. A plurality of foldably connected bed-frame sections, in combination with a seat member carried by the bed-frame at one side thereof and movable relative thereto when the bed-frame is folded and unfolded, and mechanism operable, by movements of said member relative to the bed-frame, to secure a plurality of bed-frame sections in folded

- relation and to release them when the bed-frame is respectively folded and unfolded.
4. A plurality of foldably connected bed-frame sections, in combination with a member carried by the bed-frame for different gravity movements relative thereto when the bed-frame is folded and unfolded, and complementary section fastening means carried by different of said sections, one of said means having connection with and being automatically operable by different movements of said member relative to the bed-frame to engage and release its companion when said bed-frame is respectively folded and unfolded.
5. A plurality of foldably connected bed-frame sections, in combination with a seat-frame carried by the bed-frame at one side thereof and movable relative thereto when the bed-frame is folded and unfolded, and mechanism operable, by movements of said seat-frame relative to the bed-frame, to secure a plurality of bed-frame sections in folded relation and to release them when the bed-frame is respectively folded and unfolded.
6. A plurality of foldably connected bed-frame sections, in combination with a seat-frame in movable link connection with the bed-frame for folding and unfolding movements therewith, and mechanism operable, by movements of said seat-frame relative to the bed-frame, to fasten a plurality of bed-frame sections in folded relation and to release them when the bed-frame is respectively folded and unfolded.
7. A plurality of foldably connected bed-frame sections, in combination with a seat-frame movably carried by said bed-frame at the under side thereof for folding and unfolding movements therewith, and mechanism operable, by one movement of the seat-frame relative to the bed-frame, to lock a portion of the bed-frame sections in folded relation, and operable, by a different movement of the seat-frame relative to the bed-frame, to release the locked sections to permit an unfolding thereof.
8. A plurality of foldably connected bed-frame sections, in combination with a catch member carried by one bed-frame section, a seat-frame movably connected to a different bed-frame section, and means operable, by different movements of the seat-frame relative to the bed-frame, to cause a part of the means to engage and release the catch-member.
9. A plurality of foldably connected bed-frame sections, in combination with a complementary fastening means carried by different bed-frame sections and operable to secure the same in folded relation, a seat-frame, link means connecting the seat-frame to the bed-frame for movements relative to a section thereof when the bed-frame is folded and unfolded, said link means having

connection with one of said complementary means and operable to move it into and out of engagement with its companion when the bed-frame and seat-frame are relatively moved.

10. In a device of the class described, a bed-frame having a plurality of foldably connected sections, a seat-frame carried by an intermediate section of the bed-frame for folding and unfolding movements therewith, and for movements relative thereto, and means automatically operable, by movements of the seat-frame relative to the bed-frame section by which it is carried, to lock a portion of the bed-frame sections in folded relation during a folding of the bed-frame and to release the sections during an unfolding of the bed-frame.

11. In a device of the class described, a bed-frame having a plurality of foldably connected sections, a catch-member carried by one section, a coacting stop-part carried by a different section for coacting with said catch-member to limit the relative folding movements of said two sections, a seat-frame carried by the section by which said stop-part is carried and being movable relative thereto when the bed-frame is folded and unfolded, and means automatically operable, by relative movements of said seat-frame during a folding of the bed-frame, to lock said catch-member in engagement with said stop-part, and vice versa.

12. In a device of the class described, a plurality of foldably connected bed-frame sections, one section being foldable over a second section, complementary catch means carried by said two sections, a seat-frame movably carried by said second section for folding and unfolding movements therewith, link means connecting said seat-frame and second section and one link member having connection with one of said complementary fastening means and operable, by movements of the seat-frame relative to the bed-frame, to move said connected fastening means into and out of engagement with its companion.

13. In a device of the class described, a bed-frame having a plurality of foldably connected sections, a seat-frame, crossed links pivotally connected at their crossing point and one having pivotal connection at its opposite ends with an intermediate bed-frame section and with said seat-frame, and the other having its opposite ends in shifting connection with said intermediate section and seat-frame, respectively, to permit limited inward and outward movements of the seat-frame with respect to said section, and complementary means for fastening said intermediate and an outer section in folded relation, one of said means being connected to said link member which has shifting connection with the seat-frame and bed-

- frame and automatically operable thereby, upon folding and unfolding movements of the bed-frame, to respectively engage and release its companion.
- 5 14. In a device of the class described, a bed-frame having a plurality of foldably connected sections comprising spacing and major sections, means for locking two of said major sections in folded relation, a 10 seat-frame disposed over said bed-frame when folded, link means connecting said seat-frame to one of the spacing sections for folding and unfolding movements therewith and for different movements relative thereto 15 when the bed-frame is folded and unfolded, and connection between said last means and said section locking means automatically operable to act on said locking means to lock the sections connected thereby in folded relation when the bed-frame is folded, and vice versa.
15. A plurality of foldably connected bed-frame sections, in combination with a seat-frame carried by the bed-frame for movements relative thereto, complementary fastening means carried by different of the bed-frame sections, a supporting leg carried by the seat-frame, and means connecting said bed-frame and seat-frame and automatically 20 operable to cause an engagement of said fastening means and a folding of said leg when the bed frame is folded, and vice versa.
16. A plurality of foldably connected bed-frame sections, in combination with a catch 25 carried by the outer section, a catch engaging member movably carried by an intermediate section for coöperating with said catch to secure the outer and intermediate sections in folded relation, a seat-frame, a 30 leg carried by the seat-frame, and means movably connecting said seat-frame and bed-frame and automatically operable, by rela- 35 tive movements of said frames, to move said catch-member into engagement with said catch and to fold said leg with respect to 40 the seat-frame when the bed-frame is folded, and to disengage the catch-member from said catch and to unfold the leg when the bed-frame is unfolded.
17. In a combined bed and sofa, the combination of a sectional folding bed frame, a movable seat mounted on said frame, latches mounted on the frame for locking sections of the frame together, and means connecting the seat and latches for actuating the 45 latches by the movement of the seat when the frame is being folded.
18. In a combined bed and sofa, the combination of a sectional folding bed frame, a movable seat mounted on the frame, and 50 latches mounted on the frame for locking sections of the frame together, said latches arranged to be actuated by the movement of said seat when the frame is being folded and unfolded.
19. In a combined bed and sofa, the combination of a sectional folding bed frame, a seat pivotally connected to one of said sections, latches slidably mounted on said 55 frame for locking sections of said frame together, and means connecting the latches and seat for actuating said latches when the frame is being folded and unfolded.
20. In a combined bed and sofa, the combination of a sectional folding bed frame, a movable seat mounted on said frame, an automatic means actuated by the movement of the seat for locking sections of the frame together when the frame is being folded.
- In testimony whereof, I have hereunto signed my name to this specification.

PETER J. DE DOES.
